UNITED STATES PATENT OFFICE.

GLENN H. CURTISS, OF HAMMONDSPORT, NEW YORK, ASSIGNOR TO THE CURTISS MOTOR CO., OF HAMMONDSPORT, NEW YORK, A CORPORATION OF NEW YORK.

HYDROPLANE-BOAT.

1,246,014.

Specification of Letters Patent.

Patented Nov. 6, 1917.

Application filed January 21, 1915. Serial No. 3,510.

To all whom it may concern:

Be it known that I, GLENN H. CURTISS, a citizen of the United States, residing at Hammondsport, in the county of Steuben 5 and State of New York, have invented certain new and useful Improvements in Hydroplane-Boats, of which the following is a specification.

Hydroplaning boats are now being called 10 upon to stand rough water and rough weather. This demand has come about largely through the practical application of the hydroplane to hydro-aeroplanes or flying boats. It used to be that aeroplanes ventured out upon the air or upon the water only in calm weather, but as the aeroplane has been perfected and its structure has been made more staunch and durable, aviators also have perfected their skill to an extent 15 which enables them to manipulate their craft during all ordinary weather conditions. Under such conditions it very frequently happens that the water upon which it is desired to alight is quite rough. This 20 is especially so on the ocean and in the surf even on reasonably good days. Moreover, the very speedy performance of both the aeroplane and hydro-aeroplane or flying boat has created a demand for high speed 25 seaworthy boats to serve as tenders, but the hydroplaning speed boat as heretofore constructed has not fully met the requirements. In ordinary weather they were reasonably 30 efficient, but under adverse weather conditions it has not been practicable to use them 35 freely. There have been few such speed boats having a flotation capacity sufficient to carry substantial load when standing still and the same load at extreme high speed. It 40 has been the object of my invention to produce a boat which will meet these requirements.

I have departed somewhat widely from 45 previously accepted designs. The boat of my invention instead of being long and narrow and of shallow depth is of considerable beam in proportion to its length. It has sufficient depth of flotation body to give large displacement and carrying capacity. 50 The bottom of the boat is stepped, but the stepped surfaces do not coöperate as hydroplane surfaces. The bottom of the front portion of the boat or the front of the step is a hydroplaning surface, but the bottom 55 of the rearmost portion is not so constituted,

and when the boat is planing it may and usually does occupy a position elevated from the surface of the water. One or more auxiliary hydroplaning surfaces separated from and operating independently of the front 60 hydroplaning surfaces are mounted on the hinder portion of the body and support it when in action.

According to my invention I provide three hydroplaning surfaces (thereby giving the 65 boat a three point support) and arrange these surfaces in an isosceles triangular relation with the base surfaces rearmost. The front surface is the front portion of the stepped bottom, and is of salient cross section with the apex of the angle pointing downwardly. The longitudinal elements of this surface are downwardly and rearwardly inclined at substantially the same angle from one side of the boat to the other, the inclination at the marginal portions being therefore the same as the inclination at the keel 70 portions. At the chines of the boat are provided laterally and downwardly extending bilge fins forming inverted salient angles 75 with the main body of the bottom and constituting auxiliary hydroplaning surfaces. These bilge fins may be a part of the bottom itself, (the sides of the boat being built up from their extremities), or may be mere 80 fins as stated (the sides of the boat being built up from the apexes of the angles which they make with the main body of the bottom). The front of the bottom is upwardly 85 inclined and is of a horizontal salient section of substantially the full width of the boat, although the boat may be given a cutting bow, in which event this feature will be eliminated.

The base or rear surfaces are longitudinally separated from the front surfaces sufficiently to eliminate all step action and give them an independent hydroplaning function. Preferably they are plane (though they may like the front surfaces be given a 90 slight salient angle) and are of a yielding nature, the yield being secured either as an inherent flexibility or through the use of suitable resistant springs associated with the mounting thereof.

In the bottom of the front portion of the boat is located a motor of the V-type provided with a propeller shaft which projects through the rear wall of the step of the flotation body and beneath the rear of the body 100 105 110

to a considerable depth at the stern of the boat. It lies intermediate the two base hydroplaning surfaces of the stern. At the stern there is located the operator's seat.

5 The flexibility of the stern or base hydroplaning surface gives an easy-riding quality to the stern of the boat, while the rigid construction of the front surface with the salient cross-sections effectually breaks all 10 severe impacts and prevents them from reaching the stern of the boat. The bilge fins effectually prevent side sliding on waves and markedly increase the hydroplaning efficiency.

15 In the accompanying drawings I have shown the embodiment of my invention now best known to me, but my invention may be given many other forms by those skilled in the art without departing in any wise from 20 its generic spirit.

Of the drawings, Figure 1 is a side elevation of my invention;

Fig. 2 is a cross section on line 2—2, Fig. 1;

25 Fig. 3 is a cross section on line 3—3 of Fig. 1;

Fig. 4 is a cross section on line 4—4 of Fig. 1;

Fig. 5 is a bottom plan view of the boat;

30 Fig. 6 is a cross section of the front portion of a modified form;

Fig. 7 is a plan view of a still further modification;

Fig. 7^a is a section on line a—a of Fig. 7.

35 Fig. 8 is a bottom plan view of the same;

Fig. 9 is a transverse section of the bow of the modification of Figs. 7 and 8.

The various parts of the boat of my invention are characterized and related as follows, identification being by means of reference numerals applied to drawings.

(10). *The flotation body of the boat.*—This boat as will be seen is of considerable width or beam whereby the boat when at rest is very stable. Moreover the boat is of considerable depth whereby its displacement is great and it will support in a seaworthy manner considerable load. In the form shown in Fig. 1, the bow is blunt and of substantially the full width of the boat. In the forms shown in Figs. 7 and 8 the bow is a cutting bow and is made reasonably sharp as shown in Figs. 8 and 9.

(11). *The rear wall of the step formed in the bottom of the flotation body.*—This may be but one of a plurality of steps, but the bottom surfaces of the steps have no cooperative relation with each other, and the height of the wall is made very considerable.

60 (12). *The front bottom surface.*—This surface is of salient section as shown in Figs. 3 and 4, the apex of the salient angle being centrally located and pointing downwardly, thereby constituting the portion of the bottom of greatest depth. The longitudinal ele-

ments of this front bottom surface 12 are inclined downwardly and rearwardly from the bow aft at substantially the same angle, the longitudinal inclination of the marginal and keel portions of the bottom therefore being substantially the same. The front portion of the bottom is upwardly inclined to form the blunt prow, the inclination being by a curved path and the curve being substantially the same at the margins as at the stem, and the salient horizontal front section shown in Fig. 2 being substantially the same as that of the bottom surface. The angle of this cross section may be varied at will, and as shown in the boat of the cutting bows of Figs. 7 and 8, may be gradually increasing from the bow to the stern of the surface 12. In neither case does the upwardly inclined bow portion constitute a hydroplaning surface, but is merely a water breaking surface, and therefore in the form of Figs. 7 and 8 the salient angle of the section of the bottom-most hydroplaning surface may be made uniform irrespective of that of the upwardly curved bow portion.

(13). *The bilge fins.*—These fins are laterally and downwardly inclined from the marginal portions of the surface 12, forming inverted salient angles therewith, and extending to a depth less than the depth of the apex of surface 12. They really constitute auxiliary hydroplaning surfaces. They may be formed either as fins as shown in the modification of Fig. 1 or as a part of the flotation body as shown in Fig. 6, the side wall being in the one case built up from the marginal edge of surface 12 and the other from the marginal edge of the fin 13. In either case the bottom cross section is a zig-zag the angles of which are salient and have sides of decreasing depth from the center outwardly. In both forms these fins are curved upwardly at the chines part way at least up the prow of the boat.

(14, 14'). *The stern hydroplaning surfaces.*—These surfaces are flexible, being formed of wooden plank or metal connected fixedly with the body of the boat at their front ends and fulcrumed on a suitable support intermediate their front and rear ends whereby they flex freely both between their points of support and in the rear of the same. They are arranged with respect to the front surface 12 in an isosceles triangular relation as indicated by the dotted lines in Fig. 5. They are spaced sufficiently from the front surface to eliminate cooperative action. Furthermore as shown in the form of Fig. 8 they may be supported so that their paths of travel are laterally displaced from the path of travel of the front surface 12. Their free ends project rearwardly some distance from the stern of the boat.

(15). *The driving motor.*—This motor is

preferably of the V type and is mounted in the bilge of the boat as close to the bottom as practicable. Being of the V type it can be arranged with its crank shaft very close to the keel. A propeller shaft projects rearwardly through the wall of the step and below the rear surface of the boat and supports at its outer end the driving propeller approximately at the stern of the boat and 10 in advance of the outer ends of the yielding surfaces 14, 14'.

(16). *The operator's seat.*—This is located at the extreme stern of the body 10 and is substantially the full width of the stern.

(17). *The steering rudder, which may be of any approved type and mounted in any approved manner.*—It is operated by a steering wheel or control lever located in front of the operator's seat.

20 The operation of the boat is as follows:

Any load other than the operator and passengers is placed in the body of the boat between the driving motor 15 and the operator's seat 16. According to the number of 25 passengers carried more or less of the load may be stowed adjacent to the operator's seat so as to balance effectively the weight of the motor in the front part of the boat, though precise disposition of load is immaterial.

Owing to the breadth of the frame of the boat up-setting at a standstill is practically impossible, and passengers may move around with entire freedom. There is ample room for movement over the entire boat.

35 Under way the action of the upwardly inclined prow and the hydroplaning surfaces 12, 13 and 14 decrease the draft of the body 10 as the speed is increased. In a few seconds and considerably before maximum 40 speed is reached the body 10 is elevated to such a position that it is supported entirely by the hydroplaning action of surfaces 12, 13, and 14, the under surface of the rear portion of the boat at and aft of the step 11 being above the surface of the water.

Impact with waves of large size is taken by the V-shaped bow and bottom and the wave broken. Wash from such broken waves is prevented from reaching the operator or 50 passengers by the upwardly inclined portions of the bilge fins 13. Furthermore these bilge fins by their inclination confine the water beneath the bottom of the boat, and with the broken water of impact entrain 55 reasonable quantities of air thereby materially increasing the lift of the hydroplaning surfaces 12 and decreasing their surface resistance. As the speed increases to such a point as to support the front portion of the boat entirely upon the rear portion of the surface 12, the bilge fins adjacent to step 11 act almost wholly in the important capacity of wash deflectors and under extreme speed when the wash is high and of 60 great force, as this wash strikes the bilge

fins and is thrown downwardly, outwardly, and rearwardly, thereby not only is the wash kept out of the boat, but the shock of impact is cushioned and the lift of the forward surface enhanced. When on the side of a 70 wave these fins effectually prevent skidding, acting then as planing surfaces. The rear surfaces the while support the stern of the boat clear or nearly clear of the water and by reason of the efficient action of the front 75 surface they are subjected to comparatively little shock. Such shock as does come to them, especially when their paths of movement are as shown in Fig. 5, is yielded to by them in such a manner as to be absorbed 80 before it reaches the body of the boat. Thus operators and passengers riding at the stern of the boat find riding most easy and comfortable. The boat is most easily steered, requires but a small surface for 85 steering, and does not pitch or "porpoise" under any conditions. Its speed range is extremely flexible, ranging from very low flotation speeds to extremely high hydroplaning speeds.

In the form shown in Figs. 7 and 8 the rear surfaces 14 are displaced from the sides of the boat a distance sufficient to remove them entirely from the path of travel or aspect of the front surfaces 12. This gives increased stability to the boat. In this form of boat also it will be noted from Fig. 9 that the angle of the fins 13 with surfaces 12 like the salient angle of surfaces 12 increases gradually from front to rear.

The propeller shaft 19 is stream lined, as shown in Fig. 7^a and in Fig. 7 by the provision of a fixed streamline body 18 of the section of Fig. 7^a in the vertical plane of the shaft.

The general direction of rise of the water from the step 11 is the direction of the line *a—a*. A streamline body 18 may be provided in front of the circular shaft support and extend all the way to step 11 if so desired, this amounting to a mere extension of the streamline body 18 shown. Obviously the streamline form of the body may be conveniently varied.

What I claim is:—

1. A hydroplane boat comprising a main flotation body having a portion of its underneath surface constructed in rigid hydroplaning form, together with a freely flexible hydroplaning surface longitudinally removed from it.

2. A hydroplane boat, the bottom surfaces of which form a salient angle with each other with its apex located centrally of the bottom, the longitudinal elements of said surface being inclined from the bow aft rearwardly and downwardly at substantially the same angle at the lateral marginal portions thereof as at the central or keel portions thereof, and bilge fins of substantially the 130

same inclination extending laterally and downwardly with respect to the lateral marginal portions of said bottom.

3. A hydroplane boat having a plurality of hydroplaning surfaces arranged in separated relation and acting each independently of the other, the foremost of said surfaces having a salient cross section and provided with laterally and downwardly extending bilge auxiliary hydroplaning surfaces.

4. A hydroplane boat comprising a plurality of hydroplaning surfaces longitudinally spaced apart and acting separately and independently of each other, the foremost one of said surfaces having a salient cross section with the apex pointing downwardly and provided with bilge fins at the lateral marginal portions thereof making substantially inverted salient angles with the said marginal portions.

5. A hydroplane boat comprising three hydroplaning surfaces arranged in an isosceles triangular relation, the two base surfaces being hindmost, and the front surface having a salient cross section.

6. A hydroplane boat comprising three hydroplaning surfaces arranged in an isosceles triangular relation, the base surfaces being the hindmost of the set and approximately plane, while the front surface has a salient cross section.

7. A hydroplaning boat having a flotation body the bottom of which is stepped, a driving motor mounted in said forward portion of the boat and having a propeller shaft projecting rearwardly through said step and aft beneath the rear portion of said body, the said front portion having a hydroplaning bottom of a salient cross section, the angle of which points downwardly, and the rear portion being provided with hydroplaning surfaces operating independently of said front hydroplaning surfaces.

8. A hydroplaning boat having a flotation body, the bottom of which is stepped, the bottom of the front portion thereof being V-shaped with the apex pointing downwardly, a driving motor mounted on the front portion in the apex of said V bottom and having a drive shaft projecting rearwardly from said step below the bottom of the after portion of the body, and a pair of laterally separated hydroplaning surfaces connected with said after portion of the boat and lying one on either side of said drive shaft.

9. A hydroplaning boat having a hydroplaning surface the bow portion of which is of substantially the same width as the body portion thereof, is from the bottom upwardly inclined, and has a salient cross section in a horizontal plane pointing forwardly, and the extreme bottom of which

has a salient vertical cross section pointing downwardly.

10. A hydroplaning boat having a hydroplaning surface the bow portion of which is of substantially the same width as the body portion thereof, is from the bottom upwardly inclined, and has a salient cross section in a horizontal plane pointing forwardly, the bottommost portion of the boat having a salient vertical cross section pointing downwardly, and fins projecting laterally from the bottommost surface on either side of the keel thereof and downwardly but to a depth less than the keel thereof.

11. A hydroplane boat, comprising a main body and a plurality of hydroplaning surfaces connected thereto in longitudinal relation, the foremost of said surface being of salient cross section, and fixed, and the hinder of said surface being yielding.

12. A hydroplane boat comprising a main body and a plurality of longitudinally arranged hydroplaning surfaces connected therewith, the foremost of which is of salient cross section, and fixed and the hinder of which is a plane surface yieldingly connected with the body of the boat.

13. A hydroplaning boat comprising a plurality of longitudinally spaced hydroplaning surfaces the foremost of which is of salient cross section and rigidly mounted and the hinder of which is flexible.

14. A hydroplaning boat comprising three hydroplaning surfaces arranged in isosceles triangular relation, the base surfaces being the rearmost and yielding and the front surface having a salient cross section.

15. A hydroplaning boat comprising hydroplaning surfaces arranged in longitudinal relation, the foremost of said surfaces being rigid and having a salient cross section, the hinder of said surfaces being adapted to yield in response to impact, a driving motor supported above the front one of said surfaces and an operator's seat located above the hinder of said surfaces.

16. A hydroplane boat comprising a main body having its forward underneath portion constructed in rigid hydroplaning form, and its underneath portion aft of said rigid hydroplaning surface constructed to provide a freely flexible hydroplaning surface.

17. A hydroplane boat having longitudinally spaced hydroplaning surfaces, the foremost surface being fixed and the rearmost surface freely flexible with respect to said flotation body to cushion the hydroplaning impacts.

18. A hydroplane boat including a plurality of longitudinally spaced hydroplaning surfaces, the hinder of which is flexible with respect to a fulcrum point located intermediate the ends of said hinder hydroplaning surface.

19. A hydroplane boat having a flotation body, the bottom of which is stepped and provided with a forward hydroplaning surface, and a freely flexible means secured to 5 and extending beyond the rear end of said flotation body to preclude contact of the rear bottom portion of said body with the water while hydroplaning.
20. A hydroplaning boat having a flotation body, a driving motor mounted in the forward portion of said body and having a propeller shaft projecting rearwardly aft, beneath the rear portion of said body, the 10 said front portion having a relatively fixed hydroplaning bottom, and the rear portion being provided with yielding hydroplaning surfaces operating independently of said hydroplaning bottom.

21. A hydroplaning boat having a flotation body, the bottom of which is stepped, a 20 driving motor mounted on the front portion and having a drive shaft projecting rearwardly from said step below the bottom of the after portion of said body and a pair of laterally separated hydroplaning surfaces 25 connecting with said after portion of the boat and lying one on either side of said drive shaft to extend rearwardly beyond the stern end of said body.

In testimony whereof I affix my signature 30 in presence of two witnesses.
